Specification of Letters Patent. Patented Nov. 6, 1917.

Application filed October 24, 1913. Serial No. 797,054.

To all whom it may concern:

Be it known that we, ARTHUR BATES and ARTHUR CASELTON, subjects of the King of England, residing at Leicester, Leicestershire, England, have invented certain Improvements in Lasting-Machines, of which the following description, in connection with the accompanying drawings, is a specification, like reference characters on the drawings indicating like parts in the several figures.

This invention relates to machines for use in the manufacture of boots and shoes and is herein shown as embodied in a lasting machine of the hand method type, although it will be understood that many features of the invention are susceptible of wide application.

This invention will be explained in connection with a single pincer lasting machine of the general type shown in United States Letters Patent No. 584,744, and particularly with reference to a machine of this type having a plurality of fastening inserting devices such, for example, as that shown and described in United States Letters Patent No. 1,007,051, granted October 13, 1911, on application of Arthur Bates.

In machines embodying the Bates invention there are provided two tack drivers which are carried on separate driver bars located side by side on a single driver bar carrier, the carrier being adapted to be swung about a pivot for moving the drivers into and out of tack driving position. Means is provided for raising the driver bar carrier, and a single actuating spring forces the carrier downwardly to drive the tacks, the tack drivers operating simultaneously to drive separate tacks into the work. In machines of this type there is provided means for preparing the work for the fastening operation such, for example, as mechanism for plaiting the upper or a reciprocating member for wiping the upper over the shoe bottom, for example, a tack block. This prior machine is also provided with a thick edge gage which is adapted to be brought into operation when required, usually when the plaiting mechanism is in operation, and usually has also a thin edge gage, located above the thick edge gage, which remains in place whether the thick edge gage is in operative position or not. A lever, usually a bell crank lever, is provided for moving the

edge gage into and out of operative position. At certain times, for example when plaiting takes place at the toe, it has been found disadvantageous to have both of the drivers continuously in operation as they are in this prior construction. In this prior machine the operation of one of the drivers is rendered ineffective to drive tacks by stopping the passage of tacks from the raceway and since both drivers are continuously in operation, when the supply of tacks to one of the drivers is discontinued to prevent that driver from inserting the fastenings into the work the driver will, by this continued operation drive the tack already in the holder beneath it and when it is again desired to drive two tacks it will be necessary to wait through one cycle of the machine until the tack supply device has filled the tack holder beneath the driver before two tacks can again be driven simultaneously.

One of the features of the present invention consists in a plurality of drivers arranged to drive adjacent tacks, and means for suspending the operation of one of a plurality of drivers while another driver continues in operation and while the holder cooperating with the suspended driver retains a tack ready for insertion until the operation of the suspended driver is resumed.

Another feature of the present invention consists in a plurality of independently actuated fastening inserting devices for inserting at times a plurality of fastenings, with other means for operating upon the same portion of the work as is operated upon by the fastening inserting devices, and a controller for said other means which is constructed and arranged to suspend the operation of one of said fastening inserting devices upon movement of said means. In the illustrated embodiment of the invention, which is a lasting machine, the other means referred to is employed at the more difficult part of the shoe to prepare the work for the fastening operation and the controlling means is arranged to suspend the operation of one of the fastening inserting devices when the said other means for operating upon the same portion of the work is rendered operative. The other means may comprise an upper plaiting mechanism including a plaiter controller which may occupy either of two positions. In the pres-

ent embodiment of the invention there is provided a connection from the plaiter controller to the driver and this connection renders the driver inoperative to insert tacks 5 when the controller occupies one of its positions. In the construction shown, a driver detent is provided which is normally connected with the driver and which is disconnected from the driver during movement 10 of the driver over the shoe, and the connection referred to extends between the plaiter controller and the detent and allows the connection between the driver and detent to continue when the controller occupies the 15 position to produce upper plaiting movements and effects a disconnection when the controller occupies another position.

Another important feature of the invention is found in the tack driver, in combination with a shoe gage which is movable between two positions, and a tack holder movable over the shoe bottom to present a tack in position to be acted upon by the driver, together with connections from the 25 edge gage to the driver which renders the driver operative when the edge gage occupies one of its positions. In the construction shown, the driver detent above mentioned is normally connected with the driver 30 and the connection between the edge gage and the driver is constructed and arranged to prevent such disconnection when the edge gage occupies one of its two positions and to allow such disconnection to take place 35 when the gage occupies its other position, herein shown as its rearward position.

A preferred embodiment of the invention as applied to a machine of the type specifically mentioned above will now be described 40 with the aid of the accompanying drawings. It is to be understood, however, that the invention could be applied to other lasting or like machines and that it could be embodied in a variety of forms without departing from the spirit of the invention. 45

In the accompanying drawings,—

Figure 1 is a side elevation of part of a machine of the type specifically mentioned above with a preferred embodiment of the 50 present invention applied thereto, the detent being shown in its operative position to suspend the operation of one of the tack drivers;

Fig. 2 is a front elevation of the parts 55 shown in Fig. 1;

Fig. 3 is a side elevation of part of the mechanism shown in Fig. 1 with the detent in its inoperative position so that both the tack drivers will be operated; and

Fig. 4 is a view of a detail to be referred to later.

Like reference characters indicate like parts in all the figures of the accompanying drawings.

The machine about to be described com-

prises two fastener inserting devices, 2, 4, Fig. 2, mounted on independent driver bars 6, 8, which are located side by side in a carrier 10 that is fulcrumed at 12 to the frame of the machine and is provided with means 70 to swing it about its fulcrum so as to move the drivers into and out of driving position. This means comprises the usual slide 13 which is constructed and arranged to be operated from a cam on the main shaft of the 75 machine. When the slide 13 is moved forwardly an abutment 15 on its front end comes in contact with a corresponding face 17 on the driver bar carrier 10 and swings it about the fulcrum 12 to bring the drivers 80 over the holes in the tack block 19 when the drivers reach driving position. The abutment 15 is made adjustable on the slide 13, as shown, to enable the drivers to be accurately positioned over the tack holders in 85 the tack block. Means comprising a cam 11 is also provided for lifting the driver bars and a spring is provided for each of the bars to move them downwardly so that they drive tacks into the shoe independently of 90 each other. These parts of the machine are substantially the same as those described in British Patent No. 22,071 of 1911.

In accordance with the present invention means is provided for suspending at will the 95 action of one of the tack drivers and in the embodiment about to be described the left hand tack driver, viewing the machine from the front, Fig. 2, is held inoperative while the plaiting operation is being performed 100 and while the thick or movable edge gage is in its forward position.

In order to carry this into effect there is provided a detent 14 which is mounted on one end of a rock shaft 22 journaled at 24 in 105 the driver bar carrier 10. The detent 14 is held inwardly toward the driver bar by a spring 16, one end of which is attached to an upward extension of an arm 18, and the other end of which is connected to the frame 110 of the machine. The spring 16 serves to hold the said detent in contact with a suitable recess 20 in the driver bar 6 and thus prevent the said bar from being operated by its spring 21 to drive a tack, at certain times 115 in the operation of the machine. In order to release the detent 14 and allow the driver bar 6 to be operated the shaft 22 extends through the bearing 24 formed on the carrier 10 and to the shaft 22 is secured the 120 aforementioned arm 18. The arm is provided with a hook 26 and this hook is adapted to be engaged by a hook 28 carried by an arm 30 which is pivoted at 32 to the frame 125 of the machine. When the hook 28 is in engagement with the hook 26, as is shown in Fig. 2, and the carrier 10 is swung forwardly to bring the drivers into operative position the shaft 22 of the detent 14 will move forward with the carrier, but the 130

hook 26 will be held against forward motion and thus the detent 14 will be caused to turn in the bearing 24 against the action of its spring 16 and will then be moved out of the recess 20 in the driver bar 6 so that the said bar will be allowed to be moved by the action of its spring 21 to drive a tack. On the other hand it will be understood that when the hook 28 is not in engagement with the hook 26, see Fig. 1, and the carrier is swung about its pivot, the said detent will swing bodily with the carrier and driver bar and its end will be retained in the recess 20 in the driver bar 6 by its spring 16 and consequently the said bar will be held against movement so that it will not drive a tack.

When one of the tack drivers is not in operation, of course the supply of tacks to that driver will be discontinued. One mechanism for effecting this is disclosed in the above mentioned patent to Bates.

In order to lift the hook 28 out of engagement with the hook 26 so as to prevent the operation of the driver bar 6 the arm 30 is operatively connected through a rod 36 to a lever 34 pivoted at 47 which moves the thick edge gage 9 into and out of operative position through a connection 23, so that when the edge gage is in its forward position it will, if so allowed, through its operative connections, yieldingly lift the hooked arm 30, as shown in Fig. 1.

In order to carry this into effect the rod 36, which slides through bearings 38, 40 on the frame of the machine, has at its upper end a boss 42 from which projects an arm 44, Fig. 2, engaging in a recess 31, Fig. 3, formed in the arm 30. The rod 36 is adapted to be engaged at its lower end by the face 40 of a wedge 46 yieldingly supported by a spring 48 and carried in a boss 50 on the edge gage actuating lever 34. With this arrangement when the lever 34 is turned to move the edge gage into contact with the wedge 46, it will, provided, as before mentioned, the plaiting mechanism has been thrown into operation, move the rod 36 upwardly and will raise the hook 28 out of engagement with the hook 26. When the lever 34 is moved in the other direction the arm 30 and its hook 28 will be moved downwardly by a spring 54 which is attached to the arm 30 and to the bearing 38 and thus the hook 28 will be moved into a position to be engaged by the hook 26 when the carrier is swung backwardly.

In order, however, to prevent the arm 30 from being lifted except during the plaiting operation the arm is also operatively connected to the bell-crank lever which is provided to throw into operation the said plaiting mechanism. This is effected by an inverted U-shaped lever 56 mounted to turn on the pin 32 on which the arm 30 is mounted. The lever 56 has a cam 58 formed on

its end remote from the pivot 32. The lever is acted on by a spring 60 which is secured thereto and to the frame of the machine and this spring is adapted to swing the cam 58 downwardly and hold it in contact with a roller 62 which is operatively connected to the means for throwing into operation the plaiting mechanism. The U-shaped lever 56 is secured to a sleeve 64 which surrounds the pin 32 and which is provided with a projecting arm 66 carrying a stop 68 which overlies the arm 30, Fig. 2.

The means for throwing the plaiting mechanism into operation and which control the direction and extent of the plaiting movement of the pincers 25 are substantially the same as those described in the specification of prior Patent No. 584,744, previously referred to, and comprise an arm 70 which is journaled upon a stud 72 mounted in lugs 80 projecting from the machine frame. The arm 70 is provided with a bearing 76 in which a stud 78, Fig. 2, is journaled, the stud having a bearing 80 secured to its upper end. The bearing 80 receives an extension 82 of one of two studs 84 that form the connections between bifurcated arms 86 of a bell-crank lever 88 and a collar 90 on a shaft 92 which the arms embrace. The stud 78 and extension 82 are arranged with their axes 95 at right angles to one another and are capable of sliding in their respective bearings so as to compensate for the curved paths of movement of the arm 70 and the forked arm of the bell-crank lever 88.

The collar 90 is arranged to slide upon a shaft 92 and is thereby caused to control the direction and the extent of the plaiting movement of the pincers in the known manner. The bell-crank lever 88 is pivoted at 94 and is operated through a link 96 from the usual knee lever which is not shown. To effect the sliding of the collar the arms 86 carry plates 98 which are pivoted to them by the studs 84, one of which is extended at 82 aforesaid to effect the connection with the arm 70 as previously set forth. The roller 62 is mounted on a pin 104 carried by one of the plates 98, see Fig. 4.

The cam 58 on the U-shaped lever 56 is so arranged that when the bell-crank lever 88 is rocked about its pivot to throw the plaiting mechanism out of operation the roller 62 will engage the cam 58 and will swing the lever 56 about its pivot 32 against the action of the spring 60 and will move the stop 68 on the projecting arm 66 into such a position that the arm 30 cannot be lifted, see Fig. 3.

If, on the other hand, the lever 88 is rocked so as to throw the plaiting mechanism into operation the roller 62 will be moved off the cam 58 and the U-shaped lever will be turned by its spring 60 into a direction such that the stop 68 will be moved away from

the arm 30 so that if the edge gage is then moved forward the arm 30 can be lifted through the upward pressure of the arm 44. Thus the hook 26 will be freed from the hook 5 28 and the detent 14 will remain in the recess 20 in the driver bar 6 as the carrier 10 is swung about its fulcrum to move the drivers into driving position so that the tacker will be held inoperative and only one 10 tack will be driven. When the edge gage is returned to its inoperative position it will through the connection 23 push the lever 34 and wedge 46 rearwardly and the hook 28 will be moved downwardly by its spring 54 15 so that when the tacker carrier is swung backwardly the hook 26 will engage the hook 28 and during the next forward swing of the tack carrier the detent 14 will be moved out of engagement with the recess 20 20 and the driver bar will be free to be driven by its spring.

Should the edge gage be moved forward for any purpose when the plaiting mechanism is not in operation, this forward movement of the edge gage being permitted by reason of the fact that the wedge 46 is yieldingly supported, the hooked arm will not be lifted by reason of the stop 68 on the lever 56.

Also should the edge gage be left forward when the plaiting mechanism is thrown out of operation the stop 68, as the lever 56 is swung by the roller 62 engaging the cam 58, will contact with the arm 30 and force it downwardly so that it can engage the 35 hook on the detent. It will thus be understood, that, while it is possible to drive two tacks during the plaiting operation when the edge gage is back or when the plaiting mechanism is out of operation and the edge 40 gage is forward, yet if the edge gage is forward and the plaiting mechanism is in operation then only one tack can be driven.

The cam 58 on the U-shaped lever is constituted by a rib projecting from a plate, 45 the said rib extending centrally across the said plate. With this arrangement the said cam will be engaged by the roller 62 whether the bell-crank lever is rocked so as to cause the plaiting mechanism to plait from left to 50 right or from right to left. During the plaiting operation the roller is in contact with the said plate and is located on one or the other side of the rib according as to whether the plaiting is from left to right or 55 from right to left.

Having described our invention, what we claim as new and desire to secure by Letters Patent of the United States is:—

1. A machine of the class described having, in combination, a plurality of independently actuated fastening inserting devices constructed and arranged at times to insert a plurality of fastenings, means for preparing the work for the fastening operation, 60 and controlling mechanism for said means

constructed and arranged to suspend the operation of one of said fastening inserting devices.

2. A machine of the class described having, in combination, a plurality of independently actuated fastening inserting devices constructed and arranged to insert a plurality of fastenings, other means for operating on the same portion of the work as the fastener inserting devices act, a controller to 70 render said other means operative or inoperative, and connections from the controller constructed and arranged to suspend the operation of one of said fastening inserting devices when said other means is rendered 75 operative.

3. A lasting machine having, in combination, a plurality of independently actuated fastener inserting devices adapted to insert a plurality of fastenings, means for suspending the operation of one of said fastener inserting devices, an edge gage and operative connections between the edge gage and the said suspending means whereby when the edge gage is in operative position the said 90 suspending mechanism will be operative to suspend the operation of one of the fastener inserting devices.

4. A lasting machine having, in combination, a plurality of independently actuated 95 fastener inserting devices adapted at times to insert a plurality of fasteners, an edge gage movable into and out of operative position, and means operatively connected to the edge gage for causing the operation of one 100 of said devices to be discontinued when the edge gage is in operative position.

5. A machine of the class described having, in combination, a plurality of tack drivers to insert a plurality of tacks in a shoe 105 at a single operation of the machine, a movable shoe gage, and means controlled by the position of the gage for governing the tack inserting movement of less than the whole number of the drivers.

6. A machine of the class described having, in combination, a plurality of tack drivers constructed and arranged to insert a plurality of adjacent tacks, a plurality of tack holders to present tacks in position to be 110 acted upon by the drivers, and means for suspending the operation of one driver while another driver continues in operation and while the holder coöperating with the suspended driver retains a tack ready for insertion when operation of the suspended driver is resumed.

7. A machine of the class described having, in combination, a plurality of tack drivers, means to insert a plurality of adjacent 125 tacks, a plurality of tack holders to present tacks in position to be acted upon by the drivers, tack feeding means for separating tacks during one cycle of the machine to be delivered to the holder and inserted during 130

the next cycle, and means for suspending the operation of one driver while another driver continues in operation and while the holder coöperating with the suspended 5 driver retains a tack ready for insertion when operation of the suspended driver is resumed.

8. A machine of the class described having, in combination, a tack driver, a shoe 10 edge gage which is movable between two positions, a tack holder movable over the shoe bottom to present a tack in position to be acted upon by the driver, and a connection from the gage to the driver for rendering 15 the driver inoperative when the edge gage occupies one of its positions.

9. A machine of the class described having, in combination, a tack driver, a plaiter 20 controller constructed and arranged to occupy either of a plurality of positions, and a connection from the controller to the driver constructed and arranged to render the driver inoperative to insert tacks when the controller occupies one of its positions.

25 10. A machine of the class described having, in combination, a tack driver, a shoe edge gage movable between two positions, a driver detent normally connected with the driver and between which and the driver 30 disconnection is made to take place during movement of the driver over the shoe, and means constructed and arranged to prevent its disconnection when the edge gage occupies one of its two positions and allow said 35 disconnection when the gage occupies its other position.

11. A machine of the class described having, in combination, a tack driver constructed and arranged to move over the shoe to 40 a tack driving position, a plaiter controller movable between two positions, a driver detent normally connected with the driver and between which and the driver disconnection is made to take place during movement 45 of the driver over the shoe, and means constructed and arranged to prevent said disconnection when the plaiter controller occupies one of its two positions and allow said disconnection when the plaiter controller 50 occupies its other position.

12. A machine of the class described having, in combination, a plurality of tack drivers to insert a plurality of tacks in a shoe at a single operation of the machine, independent devices for each driver adapted to 55

actuate the driver to insert a tack, a shoe positioning gage manually movable into different relations to the tacking points, and connections from said gage for suspending the operation of one of the tack drivers 60 while the gage occupies one of its positions.

13. A lasting machine having, in combination, a plurality of independently actuated drivers adapted to insert a plurality of tacks, an edge gage movable toward and 65 from the work, and means for automatically suspending the operation of one of the said drivers when the edge gage is in position toward the work.

14. A lasting machine having, in combination, a plurality of independently actuated drivers adapted to insert a plurality of fastenings, means for preparing the work for the reception of the fastenings, means for suspending the operation of one of said 70 drivers, an edge gage and operative connections between the edge gage and the said suspending means whereby when the edge gage is in operative position the said suspending mechanism will be operative to suspend the operation of one of the drivers, and connections between the work preparing 75 means and the suspending means for rendering the suspending means inoperative when the operation of the preparing means is discontinued independently of the position of the edge gage.

15. A lasting machine having, in combination, pincers which operate successively on different portions of shoe uppers, means 90 rendered operative at will for giving the pincers plaiting movements, and a plurality of independently actuated drivers adapted at times to insert a plurality of tacks, an edge gage movable into and out of operative position, means operatively connected to the edge gage and throwing one of said drivers out of operation when the edge gage 95 is in operative position, and means for rendering said throw-out ineffective when the 100 plaiting movements are discontinued.

In testimony whereof we have signed our names to this specification in the presence of two subscribing witnesses.
